UNITED STATES PATENT OFFICE.

GUSTAV SITTMANN AND WALTER H. PITTS, OF BROOKLYN, NEW YORK.

DESIGN FOR A CASE FOR COIN-CONTROLLED MACHINES.

SPECIFICATION forming part of Design No. 27,914, dated November 30, 1897.

Application filed June 10, 1897. Serial No. 640,256. Term of patent 31 years.

To all whom it may concern:

Be it known that we, GUSTAV SITTMANN and WALTER H. PITTS, citizens of the United States, and residents of Brooklyn, in the county of 5 Kings and State of New York, have invented and produced a new and original Design for a Case for Coin-Controlled Machines, of which the following is a specification, reference being had to the accompanying drawing, forming 10 a part hereof.

The accompanying drawing is a perspective view of a machine-case embodying our design.

Similar numerals of reference, wherever 15 they occur, indicate corresponding parts.

1 is the vertical front panel of the case, having a central raised cross surrounded by a raised ring and from which radiate a series of curved scrolls.

20 2, 3, 4, and 5 are openings in the upper part of the case, and 6 is a raised plate surrounding the coin-slot. The frame surrounding the

opening 5 is ornamented by a central raised cross and radiating scrollwork. A running figure, consisting of a series of raised crosses 25 connected by scrollwork, passes up the front of the case at each side 7 and 8. The end panels 10 have ornamental work consisting of a raised cross 9, surrounded by a raised ring and from which radiate scrollwork. 30

7 represent raised scrollwork at the sides of the front of the case, and 8 the ornamentation of the case-top. 9 is the end panel of the case, having ornamental work 10.

What we claim as new, and desire to secure 35 by Letters Patent, is—

The design for a case for coin-controlled machinery, set forth and described.

GUSTAV SITTMANN.
WALTER H. PITTS.
